UNITED STATES PATENT OFFICE

2,406,571

SOAP CONTAINER

Walter H. Stoehr, Cheney, Kans.

Application April 10, 1945, Serial No. 587,567

2 Claims.

(Cl. 45—28)

1

This invention relates to receptacles, and more particularly to soap receptacles.

A main object of the invention is to provide a sanitary receptacle for holding and dispensing bars of soap or the like when desired.

A further object of the invention is to provide an improved sanitary soap receptacle of novel construction.

Further objects and advantages of the invention will appear from the following description and claims, and from the accompanying drawing, wherein:

Figure 1 is a front elevational view of a sanitary soap receptacle in accordance with this invention with a portion of the front cover of one of the soap compartments broken away.

Figure 2 is a vertical cross-sectional view taken normal to the central longitudinal plane of the receptacle of Figure 1.

Referring to the drawing, 1 designates a housing which may be made of sheet metal, plastic, glass or other suitable material. Housing 1 comprises a rear wall portion 2 which extends downwardly below the body of the receptacle and is formed at its lower end portion with a perforated shelf member 3. The body of the receptacle comprises a top horizontal wall 4 and side wall portions 5, 5. The lower portions of the bottom edges of side walls 5, 5 are formed with lug members 6, 6 in which is secured a transverse rod member 7, said lug members 6, 6 being located slightly forward of the central plane of the body of the receptacle.

Pivotedly supported on rod member 7 are a plurality of channel-shaped compartments 8, each compartment being open at its forward end and being provided at its rearward end with a rear wall 9. Each compartment 8 is supported on an inverted U-shaped bracket member 10 to which it is rigidly secured, said bracket member 10 being pivotally mounted on rod 7. Rigidly secured to the bottom wall of each compartment 8 is a forwardly extending arm 11 provided with an offset push button member 12 for manually tilting compartment 8 around rod 7. A U-shaped rod member 13 is secured between side walls 5, 5 to provide a stop means for limiting the tilting of compartment 8 to an angle sufficient to allow a bar of soap contained therein to slide out for use.

Secured between side walls 5, 5 at their upper forward corner portions is a transverse rod member 14 upon which are pivotally supported a plurality of gravity-biased closure members 15, one closure member 15 being provided for each pivoted compartment 8. Secured to the rear wall 9 of each compartment is an upwardly and forwardly extending closure actuating arm 16, said arm being formed to abut closure 15 when compartment 8 is tilted and to automatically

2

raise said closure to an open position to permit the exit of the bar of soap in compartment 8, as shown in dotted view in Figure 2. Upon release of button member 12 the weight of the parts will move them back to normal position, with closure member 15 resuming its closed position and rear wall 9 abutting wall 2.

The receptacle is supported on a wall by a slotted lug element 17 secured to rear wall 2, said lug element being detachably received in a U-shaped bracket 18 secured to the supporting wall. Any other well-known detachable supporting means may be employed for this purpose.

Any desired number of compartments 8 may be employed and each compartment may be independently actuated to remove its bar of soap. The closure members 15 for each compartment will keep the soap therein clean and free from dust while not in use, and will provide a neat and pleasing appearance to the receptacle.

While a specific embodiment of a soap container has been disclosed in the foregoing description it will be understood that various modifications within the spirit of the invention may occur to those skilled in the art. Therefore, it is intended that no limitations be placed on the invention other than as defined by the scope of the appended claims.

What is claimed is:

1. A soap receptacle comprising a body member having a rear wall, a top wall and side walls connected to one another, a channel-shaped compartment pivotally supported between said side walls, said compartment being open at its forward end, means biasing said compartment to a normal substantially horizontal position, a closure member pivotally secured between said side walls and biased to normally close the forward end of the compartment, and an upwardly and forwardly extending arm secured to the rear portion of said compartment, said arm being adapted to abut said closure member responsive to tilting of said compartment.

2. A soap receptacle comprising a body member having a rear wall, a top wall and side walls connected to one another, a bottom member pivotally supported between said side walls, the plane of pivotal support thereof being forward of the central plane of said body member, the rear portion of said bottom member normally abutting and being supported by said rear wall, a front closure member pivotally supported between said side walls at their upper forward portions, and an upwardly and forwardly extending arm secured to the rear portion of said bottom member

50 for moving said closure member to an open position responsive to tilting of said bottom member.

WALTER H. STOEHRE.
